UNITED STATES PATENT OFFICE

2,112,383

HAT

Edward C. Sloan, Geneva, and Gustave Adolph Sporre, St. Charles, Ill., assignors to Jesse B. Hawley, Geneva, Ill.

Application January 31, 1936, Serial No. 61,700

4 Claims. (Cl. 2—182)

The present invention relates to hats and more particularly to the sweat band means therefor and also to a ventilating means therefor.

Among the objects of the invention is to provide a novel sweat band means whereby free ventilation of air may be effected between the head of the wearer and the crown of the hat with or without a ventilating vent in the crown, such as at the crest of the crown as also to provide a novel ventilating vent means.

Another object of the invention is to provide a novel sweat band device comprising a supporting member or auxiliary band preferably slidably connected to the crown of the hat, and a sweat or main band slidably connected to the supporting member. The supporting member in a specific illustrative embodiment is preferably in the form of a strip of material which is rigid in the direction of its width and resilient or flexible in the direction of its thickness so that it may be disposed around the interior of the crown and so shaped, as by bowing, as to hold the sweat band spaced from the crown for free passage of air. The sweat band itself is preferably made of soft material and slidably connected as by loops or slotted portions to the spaced or bowed portions of the supporting member. Both the strip or auxiliary band and the sweat or main band are adjustable in size as desired. By adjusting the auxiliary band the spacing of the bowed portions from the crown may be varied as desired, especially when fitting the main band to the particular size of the head of the wearer. For a smaller head the bowed portions extend a greater degree from the crown to hold the main or head band in proper position than for a larger head. The main band is adjustable so that it may fit and properly clasp the head of the wearer so that the hat may not be readily blown off by the wind or the like, the resiliency of the bowed portions of the auxiliary band assisting the main band in its clasping action on the head of the wearer.

Another feature of the invention is to provide a novel sweat band device which is readily attached to and detached from the hat. Where it is desired to remove the main or head band, whether to clean it or to change it for another for a new wearer or the like, the supporting or auxiliary band is easily disconnected from the crown and slipped out of the engaging or loop portion of the sweat or main band.

As a part of the means for affording free ventilation of air about or around the head of the wearer the invention comprehends a ventilating vent means preferably at the crest of the crown

of the hat which means may be readily attached to or detached from the hat.

Other objects, capabilities, advantages, features and the like are comprehended by the invention as will later appear and as are inherently possessed by the invention.

Referring to the drawings:

Fig. 1 is a side elevational view of a hat embodying the invention;

Fig. 2 is a bottom plan view of the same; 10

Fig. 3 is a fragmentary sectional view on an enlarged scale taken in a plane represented by line 3—3 in Fig. 1 of the drawings;

Fig. 4 is a fragmentary sectional view on an enlarged scale taken in a plane represented by line 4—4 in Fig. 2 of the drawings;

Fig. 5 is a fragmentary elevational view on an enlarged scale of a portion of the sweat band device, showing the means for adjusting the size of the same; 20

Fig. 6 is a fragmentary sectional view partly in section and on an enlarged scale taken in a plane represented by line 6—6 in Fig. 2 of the drawings;

Fig. 7 is a perspective view of the auxiliary or supporting band or strip; 25

Fig. 8 is a fragmentary sectional view on an enlarged scale taken in a plane represented by line 4—4 in Fig. 2 of an alternate form of auxiliary or supporting band; and,

Fig. 9 is a fragmentary sectional view taken in a plane represented by line 9—9 in Fig. 8 of the drawings.

Referring more in detail to the drawings, the embodiments selected to illustrate the invention are shown in connection with a hat comprising a 35 crown 1, a brim 2 and a crest 3. Exteriorly at the base of the crown may be provided a puggree 4 of any desired design.

The hat is preferably of the type worn during warm or hot weather or in warm or hot climates, 40 and is made of specially treated and specially processed material, such as pulp, which composes the body 5. The hat preferably has coverings 6 and 7 which may be merely a fused and solidified permanent thermoplastic of a vinyl resin base or 45 the like, or which may be textile fabric, such as cloth so treated with a thermoplastic as mentioned as to firmly bind the fabric coverings to the body of the hat.

The sweat band device comprises an auxiliary 50 or supporting member 8 of suitable material which is stiff or rigid in the direction of its width but is flexible or resilient in the direction of its thickness so that it may be bent or curved to the desired shape for the purposes of the invention. 55

This member 8 is connected to the lower portion of the crown of the hat at spaced points by clips 9 each of which has an apertured base 10 and end portions 11 and 12 which are bent over so as to provide between them and the base 10 a channel for slidably holding the member 8. These clips are preferably made of such material, as metal, as to permit the bending of the end portions 11 and 12 to either open or close the clips for removal 10 or insertion of the member 8.

The clips 9 are held in place by suitable rivets 13, preferably in the form of hollow rivets or eyelets, extending through suitable apertures provided in the hat and also through the apertures 15 of the clip bases 10 and having inner and outer flanges respectively clamping the bases 10 and the outer side of the hat as clearly shown in Figs. 4 and 8.

The main or sweat band itself may be of a single strip of material but in the embodiment chosen to illustrate the invention it is shown as comprising an inner strip 14 and an outer strip 15. The inner strip 14 is preferably of soft material such as silk or other textile fabric or may even be of soft leather or composition material so that it will be comfortable to the head of the wearer. The outer strip 15 is preferably of stiffer material and may be of a single piece or multiple. In the latter case the inner strip 15a is preferably of stiffer material and the outer strip 15b of any desired material whether soft or otherwise. The lower edge of the strip 15 is preferably turned in and secured in any suitable manner, as by stitching, to the lower edge of the strip 14 so as to form a smooth rounded edge 16 so that the sweat band in general may easily slip on to the head of the wearer, besides also forming a reinforced thickened portion at the lower part of the sweat band.

At intervals the strip 15 is provided with slits 17 and 18 so as to provide between them loop portions 19 or the like. The member 8 extends through these slits and behind the loop portions 19.

The ends 20 and 21 of the strip 8 overlap each other (see Fig. 2) and are located behind the loop portion 22 of the strip 15 at the front end of the hat. The strip or band 8 is so slid through the clips 9 and also through the slits 17 and 18 as to have bowed portions 23 so as to hold the main band spaced from the crown of the hat to provide a ventilating space and also to hold the main band to the proper size to fit the particular size of the head of the wearer. These bowed portions 23 also act as resilient means to press the main band against the head of the wearer, somewhat with the same effect as if the main band were held by the fingers at the points where the bowed portions press, thus preventing the easy blowing off of the hat by the wind or the like. As the hat tends to tip to blow off in the wind the bowed portions 23 will press harder on the windward side so as to make the main band cling more to the head, the bowed portions 23 on the opposite side still pressing because of their resiliency against the opposite side of the head.

The free ends of the main band are provided with eyelets 24 and 25 for the passage of an adjusting element 26 which may be an elastic or non-elastic cord, tape or the like and which may be loosened or drawn to adjust the main band to the particular size of the head of the wearer, and knotted as shown at 27 to maintain the size of the band.

As part of the ventilating means, there is provided at the crest 3 of the crown 1 an opening in which fits a thimble 28 having venting apertures 29, a threaded sleeve 30, and a flange 31 having a resilient lip 32 pressing against the inner side of the hat crest 3. In the sleeve 30 is adjustably threaded a screw 33 rigidly secured or fixed to a cap 34 having vent openings 35. The cap is preferably of the same composition as the hat body, that is, it comprises a body portion 36 of specially treated and specially processed fibrous material, such as pulp and coverings 37 of permanent thermoplastic material of a vinyl resin base, or textile fabric such as cloth bound fast to the body portion 36 by the thermoplastic material mentioned, or the like. This cap 34 provides therein a chamber having an inlet through the aperture 29 and an outlet through the openings 35 for the passage of air around the head of the wearer and from the crown space 20 to the exterior. In case of rain the cap 34 will shed it and prevent entry of the rain through the apertures 29. The cap is attached by simply turning it and the screw 33 to adjustably thread it in the sleeve 30, the resiliency of the lip 32 normally holding the parts in place.

In the form shown in Figs. 8 and 9, the auxiliary band or supporting member 38 preferably comprises a strip 39 which is of such material as the strip 8 described above or even of metal, such as spring metal. The strip is preferably enclosed or sheathed in a covering 40 which may be leather, composition material, textile fabric, and the like and it may be soft and flexible or it may be of stiff substance as desired. It is held 35 in the clips 9 and bowed to have the bowed portions 41 as in the case of the strip 8 described above. The inner or main band 42 may comprise a single strip or a multiple of strips of material, the inner strip portion 42a being preferably of soft material such as silk or other textile fabric, or leather, or composition material, and the like, and the outer strip portion 42b of any suitable or desirable material and which will have sufficient stiffness to hold well to the auxiliary band 38. The lower edge portion of the strip portion 42a is preferably lapped over the lower edge portion of the strip portion 42b, in any suitable manner, as by stitching or by other means of securement, so as to form a smooth 50 rounded edge 43 for smooth engagement of the band 42 with the head of the wearer. (Fig. 8). At spaced points the strip portion 42b is provided with slits to provide for loops 44 behind which the bowed portions 41 of the auxiliary band 38 are disposed as clearly shown in Fig. 9. In other respects these bands 38 and 42 are alike and have the same characteristics, properties and effects as the corresponding bands 8 and 14-15 shown in Figs. 2 to 7 inclusive and described above.

It is apparent from the disclosure that this invention has the advantage of being self adapting to the head of the wearer, as also providing for ample ventilation.

While we have disclosed a few illustrative embodiments of the invention, it is to be understood that the invention is not limited thereto but comprehends other constructions, arrangements of parts, details, materials, features and the like without departing from the spirit of the invention.

Having thus disclosed the invention, we claim:

1. A sweat band device for hats, comprising a strip of resilient material, means for connecting the strip to the crown of a hat at spaced 75

9,112,888

points, and a band of soft material having means for slidable connection to said strip at spaced points.

2. A sweat band device for hats, comprising a strip of resilient material, means for connecting the strip to the crown of a hat at spaced points, the portions of the strip between said points of connection being bowed from said crown, and a band of soft material having portions slidably connected to said bowed portions of said strip.

3. A sweat band device for hats, comprising a sweat band adjustable to a plurality of sizes, and a resilient strip slidably connected to both

said band and the crown of the hat to yieldably connect said band to said hat in spaced relationship, said connections being so arranged as to adjust the band to heads of varying sizes.

4. A sweat band device for hats, comprising a sweat band having loops on the outside thereof, clips forming loops on the inside crown of the hat and a resilient strip extending through both sets of loops to yieldably connect said band to said hat in spaced relation thereto.
